(57) **CLAIM**

The ornamental design for an adhesive tape, as shown and described.

DESCRIPTION

FIG. 1 is a front elevational view of an adhesive tape showing my new design;

FIG. 2 is a top plan view thereof;

FIG. 3 is a right side elevational view thereof;

FIG. 4 is a rear elevational view thereof;

FIG. 5 is a bottom plan thereof;

FIG. 6 is a front elevational view thereof, wherein the upper portion of the embodiment of FIG. 1 is folded rearward;

FIG. 7 is a top plan view thereof;

FIG. 8 is a right side elevational view thereof;

FIG. 9 is a rear elevational view thereof;

FIG. 10 is a bottom plan thereof;

FIG. 11 is a front elevational view of a second embodiment of an adhesive tape showing my new design;

FIG. 12 is a top plan view thereof;

FIG. 13 is a right side elevational view thereof;

FIG. 14 is a rear elevational view thereof;

FIG. 15 is a bottom plan thereof;

FIG. 16 is a front elevational view thereof, wherein the upper portion of the embodiment of FIG. 11 is folded rearward;

FIG. 17 is a top plan view thereof;

FIG. 18 is a right side elevational view thereof;

FIG. 19 is a rear elevational view thereof; and,

FIG. 20 is a bottom plan thereof.

The portions of FIGS. 1-20 shown as even broken lines are for illustrative purposes only and form no part of claimed design. Moreover, the portions of FIGS. 1-20 shown as dot-dash broken lines define, but not included in, the boundaries of the claimed design.
